(57) **CLAIM**

We claim the ornamental design for a dispensing closure, as shown and described.

DESCRIPTION

FIG. 1 is a side view of a dispensing closure embodying aspects of the invention.

FIG. 2 is another side view of the dispensing closure shown in FIG. 1.

FIG. 3 is an opposite side view of the dispensing closure shown in FIG. 1.

FIG. 4 is an opposite side view of the dispensing closure shown in FIG. 2.

FIG. 5 is a top view of the dispensing closure shown in FIG. 1.

FIG. 6 is a bottom view of the dispensing closure shown in FIG. 1.

FIG. 7 is a top perspective view of the dispensing closure shown in FIG. 1.

FIG. 8 is a bottom perspective view of the dispensing closure shown in FIG. 1.

FIG. 9 is a perspective view of a dispensing closure coupled to a container, wherein the dispensing closure embodies aspects of the invention.

FIG. 10 is a bottom view of the dispensing closure shown in FIG. 9.

FIG. 11 is a side view of the dispensing closure shown in FIG. 9; and,

FIG. 12 is another side view of the dispensing closure shown in FIG. 9.

The present application is directed to the shape and contour of a dispensing closure. Features of the drawings shown in broken lines are not considered part of the design currently sought to be patented.
